UNITED STATES PATENT OFFICE.

DAVID A. WARD, OF WARSAW, ILLINOIS.

DUST-COLLECTOR.

SPECIFICATION forming part of Letters Patent No. 450,269, dated April 14, 1891.

Application filed September 18, 1890. Serial No. 365,384. (No model.)

To all whom it may concern:

Be it known that I, DAVID A. WARD, of Warsaw, in the county of Hancock and State of Illinois, have invented certain Improvements in Dust-Collectors, of which the following is a specification.

My invention relates to dust-collectors especially adapted for use in connection with the discharge-spouts of roller-mills and with the air-exhaust pipes leading therefrom.

The object of my invention is to provide a dust-collector of a simple cheap construction, which may be easily applied and easily cleaned after a period of use.

To this end my invention consists in constructions and combinations hereinafter described, and particularly pointed out in the claims.

My invention will be more readily understood by reference to the accompanying drawings, in which—

Figure 1 is a side elevation of my novel dust-collector, portions of the same being broken away to show the construction of the device. Fig. 2 is a sectional elevation of Fig. 1, taken upon the line $x-x$ of the same. Fig. 3 shows a special application of my dust-collector.

As shown in the drawings, my dust-collector consists of two frames 18 and 19, connected together by the flexible strips 20, running clear around the inner sides of the frames 18 and 19 and closing the opening between the adjacent edges of the frame.

These frames are retained in position against lateral movement by suitable pins 22 and 23, secured in the lower frame and adapted to work in suitable slots in the upper frame, as indicated by the dotted lines in the sectioned portion of Fig. 1. The frames are normally held apart by suitable springs 24 and 25, provided between suitable side bars 26 and 27, placed upon the lower and upper frames, respectively. By placing these springs upon the side bars the springs are removed from possible contact with the cloth-strip 20, when the two sections are pressed together and the folds of the cloth are pressed out.

The cross-rods 28 and 29 are provided between the sides of the lower and upper frames and are placed, preferably, at equal distances from one another and clear across the length

of the box, as shown in Fig. 1. The sieve-cloth 30, preferably flannel, is carried alternately over the upper and lower rods 28 and 29. The edges of the piece of cloth are preferably glued to the sides of the frames and to the strips 20, so as to form a complete bar to the passage of dust. I have sometimes constructed the sieve of separate bags, the apex of each being supported by bars similar to the bars 29, while the mouths of the bags were held between bars like the bars 28. By so convoluting the sieve-cloth it is seen that a very large surface of the same is provided within a small area, thus giving the dust-collector a greater capacity than if only a simple horizontal diaphragm of sieve-cloth were used. The top of the upper frame 18 is closed by suitable box and cover 31, provided with the outlet-opening 32, leading to the exhaust-fan. A suitable hopper-bottom 33 is provided in connection with the lower frame, said hopper being provided with a suitable inlet-opening 34, adapted to coincide with the opening through which the air-current passes into the dust-collector. The current of air will be exhausted from the trough and drawn through the opening 34 into the main body of the dust-collector, where the air will pass through the fine meshes of the convoluted sieve 30 and pass on out through the top of the dust-collector and into the open air through the suction-fan. The dust, middlings, or other fine stock drawn through the opening 34 by the rapidly-moving current of air will be caught by the sieve-cloth 30 and will either drop back into the hopper or be retained in the sieve-cloth. From the hopper 34 the stock thus deposited will drop quickly and quietly into the trough leading to the elevator. When the sieve-cloth has become filled or choked with material, it may be easily cleared out by first shutting off the draft through the collector. This may be done, as shown in Fig. 3, by closing the valve 40 and striking the upper part of the frame, which will slacken up the cloth between the upper and lower rods 28 and 29 and jar out the material held therein. I preferably provide a stout cross-rod 35 above the top or roof of the dust-collector and supported upon the side blocks 36, provided upon the upper frame 18, the blows being struck upon this rod instead of on top of the

dust-collector. The shaking of the dust would be done both by the forcing down of the upper frame when a blow was struck on the bar 35 and by the sharp recoil of the frame 5 and the tautening of the cloth stretching between the rods 28 and 29.

In Fig. 3 I have illustrated one important use to which my dust-collector is applicable.

It is usual in flour-mills to connect all suction-pipes running from the several roller-mills with one large dust-collector or separation-chamber. The great objection to this arrangement is that all grades of flour and middlings are carried off by the air-currents employed for cooling the rolls and mixed together in the one separation-chamber, from thence necessarily going into a low grade of flour. If all of the grades are kept separate, the first-class middlings are eventually put into the 10 first-class flour and the lower grades into a correspondingly low grade of flour, thereby greatly increasing the market value of a given amount of stock. I accomplish this individual separation by providing one of the dust-collectors 15 in connection with the discharge-spout 67 of each roller-mill 23, as shown in Fig. 3. A shoulder or angle box 10 11 is built on each spout 67 and an opening 14 made in the top of the same, through which air passes into the 20 dust-collector from the tops of the several collectors. Pipes 15 lead to a common suction-fan 17, through which the air first drawn into the mill-easings to cool and dry the rolls therein is eventually discharged free from 25 any dust which may have first been taken up in the mills or spouts. All of the dust collected by the dust-collectors falls back into the spouts beneath them, and thence passes into the elevators 80 and to the other parts 30 of the flour-mill.

Having thus described my invention, I claim as new and desire to secure by Letters Patent—

1. The combination, in a dust-collector, of 45 the collapsible frame made up of sections joined together by suitable flexible strips, with springs arranged between said sections

and adapted to normally hold the same apart, and a convoluted sieve arranged within said sections and adapted to bar the passage of 50 dust through the opening between the sides of said sections, substantially as described.

2. The combination, in a dust-collector or bar, of the frames arranged one above the other and connected by flexible strips with 55 pins arranged between said sections and adapted to limit the lateral movement of the same in respect to one another, rods extending across said sections, sets of said rods being placed, respectively, in opposite ends 60 of said sections, with a sieve-cloth carried alternately over upper and lower rods and secured to the sides of the frames and across said flexible strips, a top for the upper frame, said top provided with an outlet, a hopper-bottom provided in connection with the lower frame and below the lower rods, an inlet-opening in said hopper-bottom, and springs adapted 65 to hold said sections normally apart, substantially as and for the purpose specified. 70

3. The combination, with the frames 18 and 19, of the flexible strips 20, adapted to close the opening between the adjacent edges of said frame and secured to the same, the pins 22 and 23, the top 31, provided with the outlet 75 32 and adapted to be secured in the upper frame 18, the hopper-bottom 33, provided in connection with the lower frame 19, the springs 24 and 25, adapted to hold said sections apart, the rods 28 and 29, adapted to 80 support the cloth sieve 30, the edges of said cloth being preferably glued to the sides of the frames, and the strips 20 to form a complete bar to the passage of dust from the hopper 33 into the upper chamber beneath the 85 cover 31, and the bar 35, provided across the top of the dust-collector and supported upon the upper frame 18, substantially as described.

In testimony whereof I have hereunto set my hand this 10th day of September, 1890.

DAVID A. WARD.

In presence of—

CHARLES ALBERS,
JOHN W. WETZEL.
